UNITED STATES PATENT OFFICE.

THOMAS CLEGG, OF ANDOVER, MASS., ASSIGNOR TO CLEGG & STEVENS.

IMPROVEMENT IN MACHINES FOR MAKING WIRE HEDDLE-EYES.

Specification forming part of Letters Patent No. 11,285, dated July 11, 1854.

To all whom it may concern:

Be it known that I, THOMAS CLEGG, of Andover, in the county of Essex and State of Massachusetts, have invented a new and useful or Improved Machine for Making Heddle-Eyes of Wire; and I do hereby declare that the same is fully described and represented in the following specification and the accompanying drawings, letters, figures, and references thereof.

Of the said drawings, Figure 1 represents a side view of a wire heddle-eye as made by the said machine. Fig. 2 is a top view of the machine. Fig. 3 is an elevation of that side of the machine on which the driving-pulley is placed. Fig. 4 is an elevation of the opposite side of it. Fig. 5 is an elevation of that end of it at which the feed-rollers are situated. Fig. 6 is an elevation of the opposite end. Fig. 7 is a transverse and vertical section taken through the main driving and twisting shafts. Fig. 8 is a vertical and longitudinal section taken through the middle of the feed-rollers, and showing the compressor-jaws.

Such other figures as may be necessary to a full and complete description of the machine will be hereinafter mentioned and described.

In the said drawings, A represents the main frame for supporting the operative parts of the machine; B the main driving-shaft, which is placed in the position as represented in the drawings, and put in revolution by an endless band, made to work around a driving-pulley, C.

At the front end of the machine is a set of feed-rollers, D E, which are placed, respectively, upon horizontal and parallel shafts F G, which shafts are made to rotate in suitable bearings, and to connect by two gears, H I, (of equal diameters,) placed, respectively, upon the said two shafts. There is a smaller gear, K, fixed on the outer end of the shaft G, such gear being made to engage or connect with a train of gears, L M N, arranged as seen in the drawings. This train receives an intermittent rotary motion by a sectoral gear, O, during the revolution of such sectoral gear, which is placed upon the side of a larger gear, P. The said gear P is fixed on one end of a horizontal shaft, Q, and receives its rotary motion by means of a pinion-gear, R, fixed on the driving-shaft B. The directions of the rotation of

the several gear-wheels are denoted by arrows marked upon them. The upper feed-roller is pressed down toward and upon the other, or the wire made fast between them, by means of a spring, S, which is applied to a stirrup, T, that embraces the shaft of the upper feed-roller near one end of it, the bearing of such end of the shaft being so made as to allow of a little vertical play to the shaft.

In the drawings, U represents the wire from which the eyes are to be formed. It is passed in between the two feed-rollers, and by them fed forward toward the bending and twisting machinery as fast as occasion may require. From the feed-rollers the wire passes through a round hole made in a stationary steel plate, V, which has on its rear side a knife, W, the office of which is to cut off the wire or separate from it a piece of sufficient length to form a heddle-eye. A rear side view of this knife and the plate V is given in Fig. 9. The said knife, formed like one of the blades of a pair of shears, turns on a fulcrum or pin, X, and is moved away from the wire during the time that a sufficient length of it to form a heddle-eye is passing through the steel plate V by means of a cam, Y, fixed upon the side of a gear-wheel, Z, fixed upon the shaft Q. As soon as this cam ceases to act upon the lower end of the lever of the knife W, a spring, a, applied to the lever and the frame, is set free, so as to react and move the knife against the wire and cause said knife to separate from the wire a blank or piece of sufficient length for the formation of the heddle-eye. On passing onward from the plate V the wire is made to extend into and work through two guide-pliers, b c, whose purpose is to receive the end of the wire and guide it properly toward the pin, around which it is afterward bent. Each of these guide-pliers is provided with a short semi-cylindrical groove, d, which has a flaring mouth, e, as seen in Fig. 10, (which is a top view of the lower and stationary part, b, of the guide-pliers,) the under side of the upper guide-wire-plier c being formed with a similar groove. The said guide-plier c is a bent lever turning on a fulcrum-pin, f, and operated in one way by a cam, g, (fixed on the shaft F,) and in the other by a spring, h, which presses the tail end of the lever against the shaft and cam.

A side view of this cam and the lever and spring is given in Fig. 11. After having passed through the guide-pliers in part, the wire is received upon a bed or flat surface, *i*, formed upon the end of a rotating shaft, *k*, the said wire being made to rest at its middle against a small stud or pin, *l*, which projects upward from the bed *i*, as seen in the drawings. Behind the wire and pin *l*, and on the flat surface *i*, there is a slider or bender plate, *m*, which is made to slide freely in a longitudinal direction upon the shaft *k*. The said slider has a notch, *n*, formed in its end which is next adjacent to the pin *l*, such notch being formed of a width equal to the diameter of the pin *l* added to twice the diameter of the wire. At a proper time the slider or bender *m* is forced against the wire so as to bend it on and against the pin *l*, the movement of the slider being effected by means of a lever, *o*, which turns on a fulcrum, *p*, and is moved by a small cam, *q*, placed upon the shaft *Q*. A side view of the lever and the cam is given in Fig. 12. The back movement of the lever and the slider or bender is produced by the reactive power of a spring, *r*. The bender should be so applied to the lever *O* as to allow of the rotation of the shaft *k* during the operation of twisting the wire, which operation will be hereinafter described.

The next portion of the machinery to be described is that by which the wire is held or supported during the twisting operation. A part of this machinery consists of a stationary rest, *t*. Another part, *s*, may be called the "movable die." An underside view and edge and side views of this die are given in Fig. 13, wherein it is shown as formed of three projections, *u v w*. One of these projections—viz., the middle one, *v*, when the movable die is depressed—is carried between the two bent legs of the wire blank, while each of the other projections, *u w*, is made to project down outside of one of the legs of the wire blank. When the movable die is depressed one of the legs, or half of the wire blank, is supported on the stationary rest *t*. The movable die *s* extends downward from an arm, *x*, that projects from a vertical slide, *y*. The slide *y* is supported in stationary bearings, *z z*, and is jointed at its lower end to a rocker-lever, *a'*, that is depressed at its opposite end by a spring, *b'*, and elevated by a cam, *c*, fixed upon the inner side of the large gear, *P*, hereinbefore described, such cam being shown in Fig. 14, which is a side view of it and the gear *P*. When the two halves of the wire blank are bent around horizontally and into parallelism with one another, they are received between two jaws, *d' e'*, which are sustained by a movable carriage, *f'*.

In Fig. 15 is given a longitudinal section of the said carriage and its jaws, and the rod *g'*, upon which it moves horizontally. The said carriage is supported so as to move freely on the said rod, while the said rod is maintained in a perfectly stationary position, as seen in the drawings. The lower jaw, *e*, is a station-

ary jaw—that is to say, it is firmly fixed to the carriage, while the upper jaw is a movable one, or is so attached to the carriage as to be capable of freely sliding upward or downward. It is pressed down toward the stationary jaw by means of a spring, *h'*. The said movable jaw is also pressed downward toward the stationary jaw by means of a vertical slide-frame, *i'*, which is fixed upon the top of a slide-rod, *l'*, and is elevated by a cam, *m'*, (fixed upon the shaft *Q*.) and depressed by the action of a spring, *n'*, suitably connected to the slide-frame. Projections *o' o'* extend upward from the slide-frame *i'* and a short distance over the movable jaw *d'*. From the lower jaw there is a small stud, *p'*, made to project inward and upward a short distance above the die. When the wire is bent around, its two legs or parts are made to embrace the said stud *p'*, and by said stud they are kept at a suitable distance apart. It should be borne in mind that during the time the wire blank is being so bent the two jaws *d'* and *e'* are separated so as to receive it, such separation of them having been previously effected by the elevation of the upper jaw, produced by the action of the cam *m'*, such cam having raised the vertical slide-frame *i'* and forced it against the upper jaw, so as to elevate such jaw into the position required.

Directly underneath the shaft *k* is another horizontal shaft, *q'*, whose axis is parallel to that of the shaft *k*. The said two shafts are connected by gears *r' s'*, the lower one of which—namely *s'*—is made to engage with and is moved by the sectoral gear *O* during the revolution of said sectoral gear. From the above it will be seen that both shafts *k* and *q* receive a simultaneous rotation while the lower shaft is being rotated. There is on the lower shaft, *q'*, a sliding gear, *t'*, which is connected to the shaft by a spline or feather, or such a connection as will enable it to slide freely on the shaft and be rotated by the shaft when the shaft is put in revolution.

Affixed to the inner face of one side of the frame there is a vertical slide or carriage, *u'*, which supports a rotary notch-gear, *v'*, on a tubular arbor, *w*, which arbor revolves in the carriage.

Fig. 16 is a side view of the carriage *u'* and the gear *v'*. Fig. 17 is a vertical section of the same. The said rotary gear *v'* is provided with a notch, *x'*, which extends downward between its teeth and to or below its middle, and has a small pin or stud, *y'*, projected upward from the bottom of it, (the notch,) this pin serving to aid in the formation of one of the end eyes of the article made by the machine. When the wire blank has entered between the jaws *d' e'*, the rotary gear *v'* is elevated or raised upward so as to receive the blank within its notch *x'*, and so that the stud or pin *y'* shall pass between the two halves or legs of the wire blank. The elevation of the rotary gear *v'* and slide *u'* is produced by a cam, *z'*, which acts against a rocker-lever,

a^2 , that is jointed to the carriage u' . The said cam is fixed on a shaft, b^2 , that receives its rotary motion by means of a gear, c^2 , that engages with the gear Z , hereinbefore described. The depression of the carriage u' is produced by the reacting power of a spring, d^2 , arranged as seen in the drawings. As soon as the rotary gear v' is elevated above the slide-gear t' , such slide-gear is, by a spring, e^2 , thrown forward into gear with the rotary gear v' . Next, the sectoral gear O comes into operation with the gear s' and produces a simultaneous rotation of the shafts $q' k$ and the rotary gear v' . While this is taking place the wire blank is held firmly on the pins l and y' , and by means of the stationary rest t and the movable die s , and also by the two jaws $d' e'$. The consequence is that the wire blank will be twisted between the pin l and the movable die s ; also between the movable die s and the pin y' , and also between the pin y' and the stud p' . At the next operation the slide-gear t' is moved backward by the action of a fork-lever, f^2 , the upper ends of the fork of said lever being provided with inclined planes or cams $g^2 g^2$, which are thrown up, respectively, against arms $h^2 h^2$, that extend from a tubular shaft, i^2 , of the slide-gear t' . The forked arm of the lever f^2 is depressed at the proper time by a cam, k^2 , that is fixed on a shaft, b^2 , and made to act against a stud, l^2 , projecting from the tail end of the fork-lever. Said forked arm is also raised at the proper time by the reacting power of a spring, m^2 . As soon as the slide-gear t' has been moved backward, and beyond the rotary gear v' , the said rotary gear v' is depressed entirely below the wire blank. When the vertical slide-frame i' is depressed so as to force the jaw d' toward the jaw e' , it carries a forked piece of metal, n^2 , down upon and astraddle of the stud p' and the wire blank, the same serving to hold the wire blank close against the stud. When the slide-frame i' is elevated, it, as a matter of course, will lift the fork n^2 entirely above the stud p' . This being the case, the next operation is to move the carriage f' on its rod g' , so as to carry the twisted wire blank in between the flattening jaws, as will be hereinafter described. Before, however, this can be accomplished, a small projection, o^2 , that extends upward from the fork of the fork-lever f^2 , has been elevated against the wire blank, so as to throw it entirely off the pin l , such elevation of such projection occurring at the time of the elevation of the fork-lever, as hereinbefore described. The movement of the carriage f' is effected by the action of a rocker-arm, p^2 , which is formed as seen in Fig. 4, and turns upon a fulcrum-pin, q^2 , arranged at its lower end. A bent arm, r^2 , extends from the arm p^2 , as seen in the said figure, and is acted upon by a cam, s^2 , placed in the outer end of the shaft b^2 . The upper end of the arm p^2 is forked and straddles a screw-pin, t^2 , projecting from the carriage f' , which carriage is moved in one direction on its rod g' when

the cam s^2 acts against the bent arm r^2 . The return of the carriage or movement in the opposite direction is produced by the reacting power of one or more springs, $u^2 u^2$, applied to the main frame and the arm p^2 , as seen in Fig. 4.

We have heretofore spoken of the pressure-jaws. They are shown at $v^2 v^2$, the lower one—namely w^2 —being stationary, while the upper one is movable, or is fixed upon a lever, x^2 , which turns upon a fulcrum, y^2 , and has its tail end elevated by a cam, z^2 , fixed upon a shaft, a^3 , which receives its rotations from a train of gears, b^3 , c^3 , and d^3 , made to engage with the gear P . The object of the pressure-jaws is to firmly compress the metallic eye, and particularly the twists thereof, and so flatten said twists as to make them in thickness in one direction equal to or about equal to that of the wire used. The object of this flattening or compression of the twists is to prevent the warp-thread, when the metallic heddle or eye is used, from sticking or catching in the twists of the wire. When the carriage f' is moved upon its rod g' toward the compressor-jaws, these jaws are open to receive the twisted wire blank which is carried in between them, and they are firmly closed upon it and perform their office of compressing the twists of it. This being accomplished, a lever, e^3 , is moved by a cam, f^3 , (placed upon the shaft a^3), against the jaw d' , and lifts it above the blank, so as to entirely release the said blank from the carriage f' and allow the blank to remain between the compressor-jaws while the carriage is moved backward into the position for the reception of the next blank. During the backward motion of the carriage the blank is discharged from the presser-jaws (they being supposed to be open) by the action of the stud p' , or small stud g^3 , placed upon and made to project from the inner side of the carriage. If desirable, a small knife may be applied to the side of the presser-jaws, and so made to operate as to cut off the surplus portions of the eye-blank previous to its discharge from the compressor-jaws. The upper jaw of the compressor-jaws may be moved away from the lower jaw by the weight of the tail of its lever, or by additional weight, or a spring applied thereto.

Having thus described my machine, what I claim therein as of my invention is as follows:

1. The combination of presser jaws or mechanism with machinery for doubling and producing the twist in the wire, as above set forth, the said pressure-jaws or compressing mechanism being for the purpose of flattening the twists of the wire substantially in the manner and for the purpose as specified.
2. And in combination with the presser jaws or mechanism and the mechanism for producing, doubling, and twisting the wire blank, the movable carriage f' and its jaws $d' e'$, or mechanical equivalents therefor, as made to

operate substantially in manner and for the purpose as above set forth.

3. The combination of the stationary rest *t* and movable die *x* with the slider or bender *m*, the shaft *k*, and the rotary notch-gear *v'*, the whole being made to operate together substantially in manner as hereinbefore specified.

In testimony whereof I have hereto set my signature this 21st day of February, A. D. 1853.

THOMAS CLEGG.
